United States Patent

Des. 236,146
Patented July 29, 1975

236,146

TOY VEHICLE

Philip F. Seymour, Plymouth, Minn., assignor to
Tonka Corporation, Hopkins, Minn.

Filed Dec. 28, 1973, Ser. No. 429,356

Term of patent 3½ years

Int. Cl. D21—01
U.S. CL. D34—15 AJ

FIG. 1 is a top front perspective view of a toy vehicle showing my new design;

FIG. 2 is a top plan view thereof;

FIG. 3 is a left side elevational view thereof;

FIG. 4 is a front elevational view thereof;

FIG. 5 is a rear elevational view thereof; and

FIG. 6 is a vertical section taken on line 6—6 of FIG. 3.

I claim:

The ornamental design for a toy vehicle, as shown.
